HONING SPINDLE

Arthur F. Wedge, Hartford, and Homer T. Bidwell, Manchester, Conn., assignors to Colt's Manufacturing Company, a corporation of Connecticut

Application December 4, 1943, Serial No. 512,928

8 Claims. (Cl. 51—184.3)

1

This invention relates to improvements in honing mandrels or spindles.

The invention is particularly applicable, though not restrictively, to a honing mandrel or spindle of the type utilized in conjunction with a grinding or honing machine such as illustrated and described in Patents Nos. 2,070,381 and 2,117,525, both in the name of Joseph Sunnen.

One type of standard or conventional honing spindle now used with the honing machines referred to comprises an elongated longitudinally splined shank having on its outer free end a diametrically enlarged portion accommodating the honing member or grinding stone which projects radially from the spline. The outer surface of said enlarged end opposite the radially projecting honing member or stone serves as a bearing or backing for the latter when the spindle is used to hone the inner surface of a cylindrical aperture in a work piece.

Means are provided in the spindle and honing machine to cause the honing member to be expanded radially as said member wears. The opposite surface referred to on the outer end of the spindle also rubs against the inner surface of the aperture being honed and the abrasive particles accumulating on the surface of the aperture as the stone wears serve to grind or wear away the surface of the enlarged outer end of the spindle opposite the honing member. Ultimately, and rather rapidly, the portion of the enlarged outer end of the spindle opposite the honing member becomes worn down to where it is merely a continuation of the main or intermediate portion of the spindle and no longer gives the proper backing to the honing member in the spindle. Inasmuch as said enlarged outer end of the spindle is integral with the shank to which it is attached, when said enlarged outer end becomes worn to the extent referred to above, it is necessary to discard the spindle and insert a new one in the machine.

Particularly in spindles which are relatively long in comparison to their diameter, it is necessary to form the spindles of high quality tool steel in order to provide the proper strength. Such strength is especially necessary where the spindles are longitudinally splined as in the type to which the present invention pertains. From actual experience, it has been found that in certain types of spindles of the nature described, the effective "life" thereof is about as long as six of the honing members of a particular abrasive composition used therein. Furthermore, in situations where the honing machines are used constantly during

2

an eight hour day on a certain type of material, approximately four spindles will be worn each day to the extent they are no longer usable and discarding thereof is necessary.

From the foregoing, it will be seen that the required discarding of four spindles per eight hour day from each machine amounts to a considerable waste of good quality tool steel, particularly when the fact is considered that the major portion of the spindle is still in satisfactory condition for continued use and the only unusable part is the outer enlarged end which has been worn to an unusable condition.

It is therefore an object of the present invention to improve the construction of the conventional or standard type of spindles referred to above to the extent that the enlarged outer end of the spindles is formed by adding a detachable cylindrical sleeve to the outer end of a shank having a uniform diameter except at its shank end, the thickness of the wall of said sleeve being adequate to furnish the required enlargement needed at the outer end of the spindle to provide a proper backing or bearing surface for the honing member disposed in the spline of the spindle, whereby when said enlarged outer end formed by the sleeve is worn to such extent it is no longer usable, the worn sleeve may be replaced by a new one and the continued use of the main portion of the shank is thus possible.

It is another object of the invention to provide a number of different embodiments or types of disengageable connecting means by which the renewable sleeves referred to above are operatively secured to the outer or free end of the spindle.

It is a still further object of the invention to construct the connecting means comprising the last-mentioned object in such a way that at least several embodiments of the connecting means will utilize constructions on the present standard type of spindles whereby previously discarded spindles may be inexpensively revised to include a sleeve construction comprising the present invention to thus result in considerable saving in material formerly considered waste, notwithstanding the fact that the present invention is even more readily applicable to spindles being newly manufactured.

The details of the invention and the foregoing objects, as well as other objects of the invention, are given in the following specification and illustrated in the accompanying drawings forming a part thereof.

The accompanying drawings show the embodiment of the invention which is deemed preferable,

but it will be understood that the drawings are intended for illustrative purposes only and are not to be construed as defining or limiting the scope of the invention, the claims forming a part of this specification being relied upon for that purpose.

In the drawings,

Fig. 1 is a fragmentary side elevation of sufficient details of a honing machine, including a standard or conventional honing spindle operatively positioned in a diagrammatically shown work piece, to illustrate the construction over which the present invention comprises an improvement.

Fig. 2 is an enlarged end elevation of a standard honing spindle of the type illustrated in Fig. 1, the end of said spindle being shown in a cylindrical aperture in a diagrammatically illustrated work piece, the spindle illustrated being in new or originally manufactured condition.

Fig. 3 is a view similar to Fig. 2 but showing the outer end of the spindle after it has become worn to the extent that it is no longer usable.

Fig. 4 illustrates a fragmentary side elevation of the outer end of a spindle made in accordance with one embodiment of the present invention.

Fig. 5 is a side elevation of a renewable sleeve comprising part of said embodiment of the invention and adapted to be detachably secured to the end of the spindle shank shown in Fig. 4.

Fig. 6 is a fragmentary side elevational view showing the sleeve illustrated in Fig. 5 assembled in operative position on the end of the spindle shown in Fig. 4.

Fig. 7 is a sectional end elevation on the line 7—7 of Fig. 6 and illustrates one embodiment of connecting or locking means for detachably securing said spindle and sleeve in assembled relationship.

Fig. 8 is a side elevation of a sleeve similar to that in Fig. 5 but embodying another form of means for securing the sleeve to the outer end of a spindle such as shown in Fig. 4.

Fig. 9 is a fragmentary side elevation illustrating the sleeve in Fig. 8 assembled on the outer end of a spindle such as shown in Fig. 4.

Fig. 10 is a sectional end elevation on the line 10—10 of Fig. 9 and illustrates another embodiment of connecting or locking means for detachably securing the spindle and sleeve in assembled relationship.

Fig. 11 is a sectional view similar to Fig. 10 but shows the relative position of the sleeve and outer end of the spindle at the time the sleeve is being telescopically assembled on the spindle and before the sleeve assumes its operative position on the spindle as illustrated in Fig. 10.

Fig. 12 is a fragmentary side elevation similar to Fig. 4 but illustrating the outer end of a spindle including another embodiment of locking means comprising the present invention.

Fig. 13 is a side elevation of a sleeve to be used with the spindle shown in Fig. 12.

Fig. 14 is a fragmentary side elevation showing the sleeve shown in Fig. 13 assembled in operative position on the end of the spindle shown in Fig. 12.

Fig. 15 is a sectional end elevation on the line 15—15 of Fig. 14 and illustrates the details of the means illustrated in Figs. 13 and 14 for securing the sleeve and spindle together in operative relationship.

Referring to the drawings, Fig. 1 shows a fragmentary portion of a honing machine utilizing a spindle to which the present invention per-

tains. Only the essential portions of the machine which control and drive the spindle have been illustrated. For a complete understanding of the machine, attention is directed to the two patents mentioned in the foregoing.

In Fig. 1, a supporting frame 10 rotatably supports a tubular shaft 12 which is adapted to be rotated by any suitable means such as a pulley 14. The end of the shaft 12 opposite that secured to the pulley is formed so as to provide a cylindrical socket 16 adapted to receive the shank 18 of a honing spindle 20. Said honing spindle 20 is of the standard or conventional type now used with the type of honing machines referred to in the foregoing.

As clearly illustrated in Fig. 1, the shank 18 of the spindle 20 is considerably enlarged in diameter over that of the main portion of the spindle. Further, the outer free end 22 of the spindle is enlarged diametrically as is clearly evident in said figure. The entire spindle including shank 18 and enlarged portion 22 is conventionally formed from a single piece of stock, the main or intermediate portion of the spindle, as well as the diametrically larger outer end being cut down to produce the shape shown in Fig. 1.

The spindle 20 is provided longitudinally from end to end with a spline 24, said spline being of sufficient width to receive therein, adjacent the outer end of the spindle, a honing block or member 26 which usually comprises a metallic base 28 to which is suitably cemented a grinding or honing stone 30.

The honing member 26 is adapted to be radially expanded with respect to the outer end of the spindle by means of a flat bar 32 connected at one end, in the spline in the shank of the spindle, with a longitudinally adjustable member 34 mounted in and rotatable with shaft 12. Member 34 is movable in opposite directions, as indicated by the arrows thereon, and is normally biased toward the left as viewed in Fig. 1, by helical spring 36.

The opposite or outer end of bar 32 is provided with a pair of cams 38 and 40, the cam faces of which are parallel but longitudinally spaced so as to be coengagable with a pair of suitable spaced and parallel cam surfaces 42 and 44 formed in a recess on one side of the metallic portion 28 of honing member 26. As bar 32 is moved outward toward the end of spindle 20, the coengaging cam surfaces thereon and on the honing member will cause the latter to be expanded radially outward. Such movement is insured due to the fact that the honing member 26 is prevented from moving longitudinally with respect to the spindle 20 by means of a pin 46 which projects from one side of the honing member and is accommodated in a vertically extending recess or slot 48 in the spindle which recess extends laterally from the spline 24. Said slot permits movement of the honing member 26 in a radial direction only with respect to the spindle.

The honing machine described in the patents referred to in the foregoing is provided with means whereby the operator may readily move member 34 and bar 32 in opposite directions while the spindle 20 is rotating in a work piece 50 indicated in dotted lines in Figs. 1 through 3 for purposes of honing the surface of a cylindrical aperture 52 in said work piece. An experienced operator can readily ascertain from the "feel" of the machine while it is operating whether the

honing member 26 is sufficiently expanded to perform the honing operation in a satisfactory manner. If said honing member is not sufficiently expanded, the machine is provided with means whereby member 34 and bar 32 may be moved axially outward toward the end of the spindle to expand the honing member the proper amount.

When it is desired to remove the honing tool from the work piece, the control means on the machine for member 34 and bar 32 are released, whereby spring 36 automatically retracts bar 32 and permits honing member 26, through engagement with the surface of the aperture 52 in the work piece, to be moved radially into the spline 24 sufficiently to permit ready withdrawal of the outer end of the spindle from the aperture 52.

The portion of the enlarged end 22 on the spindle opposite the honing member 26 provides a bearing or backing surface to maintain the honing member in honing engagement with the surface of an aperture such as 52 in a work piece. As has been briefly mentioned above, however, the abrasive particles wearing away from the stone 30 of the honing member will remain in the aperture and will serve in a detrimental capacity to wear away said opposite portion of the enlarged end 22 of the spindle. When the spindle is in new and unused condition, the enlarged outer end thereof will appear in end view as shown in Fig. 2. However, after said opposite portion of the enlarged outer end has become worn, the surface of said portion will be substantially in alignment with the intermediate portion of shank 20 so that the end of the spindle will resemble the view shown in Fig. 3.

Usually, when a spindle becomes worn to the extent illustrated in Fig. 3, and particularly after the stone of the honing member becomes worn more or less to the extent shown in said figure, the spindle and honing member are no longer usable for purposes of honing the surface of a cylindrical aperture having a diameter of the size which said spindle and stone were intended to hone when in new condition. When thus worn, the stone and spindle must both be discarded and replaced. Inasmuch as the enlarged outer end of the spindle is integral therewith in the conventional construction thereof, it is necessary to discard the entire spindle in accordance with present practice. As stated above, the honing members 26 will usually wear considerably faster than the enlarged outer end of the spindle, whereby each spindle will outlast a number of honing members per se. However, the outer end of the spindle will ultimately become worn to the extent that it will have to be discarded in addition to the worn honing members.

The present invention contemplates overcoming the waste comprising discarding the entire spindle when the outer end thereof becomes too worn for further use by forming the outer end of the spindle 20 with an outer diameter uniform with the major portion of the spindle such as illustrated in Figs. 4 and 6. The enlargement of the outer end of the spindle is effected by providing a sleeve 54 having an inner diameter substantially equal to the outer diameter of the end of the spindle and an outer diameter adequate to produce an enlargement on the end of the spindle of proper dimensions to provide the required backing or bearing surface for the honing member when disposed in the spline in the spindle.

Such a sleeve is shown in Fig. 5 and is substantially as long as the length of the enlarged por-

tion 22 on the outer end of a conventional spindle. Sleeve 54 is thus adapted to telescopically engage the outer end of spindle 20 when formed as described above, and said sleeve is provided with an inward projecting lug or pin 56 for purposes of being disposed in the slot 48 normally formed in the end of a conventional spindle to prevent relative longitudinal movement of the honing member and also formed in the modified spindle for the same purpose. The utilization of such a slot is advantageous to not only detachably lock the sleeve 54 against movement with respect to the spindle 20 in a longitudinal direction but, such utilization of the conventional slot 48 to comprise part of said locking means enables the salvaging of previously discarded spindles. Such salvaging may be effected by cutting the worn enlarged outer ends of the discarded spindles until said outer end of each has a diameter equal to that of the intermediate portion of the spindle. Sleeve 54 is also provided with a longitudinally extending slot 58 adapted to be aligned with spline 24 to accommodate and permit radial projection therefrom of a honing member 26. Pin 56 is preferably disposed longitudinally of the sleeve in such a position that, when disposed in slot 48, the outer end of the sleeve is substantially flush with the outer end of the spindle.

Sleeve 54 is also provided with a transverse slot 60 extending outward from the longitudinal slot 58 sufficiently far to permit passage therethrough of pin 46 on the honing member when said honing member is being mounted in the spline of the spindle. Thus, pin 56 on the sleeve and transverse slot 60 therein are in transverse alignment with respect to said sleeve. Furthermore, pin 56 is mounted on said sleeve in such position that it will be disposed in the lowermost portion of slot 48 when assembled in operative position as shown in Fig. 7, whereby there will be no interference between pin 46 on the honing member and pin 56 on the sleeve when the honing member is assembled in the spindle.

When the sleeve and spindle are assembled as illustrated in Figs. 6 and 7, it will thus be seen that honing member 26 when disposed in the aligned slot and spline therein will prevent relative rotational movement between sleeve 54 and spindle 20. Thus, the honing member and pin 56 on the sleeve when disposed in slot 48 in the spindle serve to maintain the sleeve operatively assembled with the outer end of the spindle.

Fig. 8 shows another embodiment of the invention similar to that shown in Figs. 4 through 7 but in which the sleeve 54 is provided with a transverse slot 62 positioned similarly to slot 60 of the previously described embodiment but extending a greater distance transversely from longitudinal slot 58, slot 62 being provided at its closed end with an inturned tongue 64 which serves a function similar to pin 56 in said previously described embodiment. Tongue or ear 64 extends inward substantially the same distance as pin 56. Otherwise, the latter embodiment of the invention is similar both physically and in function to the previously described embodiment.

The sleeves 54 comprising the two embodiments of the invention described above are assembled on the outer end of spindles 20 by telescopically sliding said sleeves part way on said spindles and then rotating said sleeves until either the pin 56 or the ear 64 is disposed in longitudinal alignment with spline 24, as shown in Fig. 11. Then the sleeves are moved longitudinally onto the spindles until said pin 56 or ear 64 is in trans-

verse alignment with slots 48 in said spindles. The sleeves are then rotated in the direction of the arrow shown in Fig. 11 until either the pin 56 or ear 64 is disposed substantially against the closed end of slot 48. Longitudinal slots 58 in the sleeves will then be in alignment with splines 20 for purposes of receiving the honing members.

The sleeves may be disassembled from the spindles, such as when the former have become worn, by first removing the honing members and then rotating the sleeve reversely to the arrow shown in Fig. 11 until the pins or ears are disposed in the splines, following which the sleeves are moved longitudinally outward from the free ends of the spindles.

A still further embodiment of the invention is illustrated in Figs. 12 through 15 in which the outer end of the spindle 20 has the same diameter as the main portion of the spindle and said end of the spindle also has the conventional transverse slot 48 therein which receives pin 46 on the honing member. However, said embodiment includes different locking means for securing the sleeve to the spindle, said locking means comprising a relatively wide slot or groove 66 extending transversely to the spline 24 and inward from the outer surface of the spindle adjacent said spline. Said groove is located in the spindle further inward than slot 48 and is positioned to receive an inturned ear or tongue 68 provided on a sleeve 70 which is otherwise similar in dimensions to sleeve 54 shown in the other figures of the drawings.

Ear 68 is formed adjacent one end of the sleeve 70, said end being opposite to that adjacent which slot 60 is formed for accommodating pin 46 of the honing member. It has been found that the ear 68 of the latter embodiment of the invention may be less expensively formed than the pin 56 or tongue 64 included in the previously described embodiments inasmuch as the formation of ear 68 requires only making a single transverse cut extending inward from one wall of longitudinal groove 58, following which the portion of the sleeve which is to form the ear is bent inward as indicated in Figs. 13 through 15.

The sleeve comprising the latter embodiment of the invention is assembled and disassembled with respect to the spindle in the same manner as the sleeves comprising the other embodiments of the invention.

It will thus be seen that the various embodiments of the present invention will permit the effecting of considerable economy in honing spindles of the type described since, when the present invention is utilized, the only worn items which need be discarded are the replaceable sleeves and thus considerable material and expense is saved in contrast to using the conventional spindles wherein the entire spindle had to be discarded when worn to the extent that it was no longer usable. Furthermore, the sleeves comprising the various embodiments of the present invention may be expeditiously attached to and removed from the outer ends of the spindles. In addition, the various constructions comprising the invention are rugged and durable and readily adaptable not only to spindles being newly manufactured but also to existing spindles by only slight modifications thereof.

While the invention has been illustrated and described in its preferred embodiments and has included certain details, it should be understood that the invention is not to be limited to the precise details herein illustrated and described since

the same may be carried out in other ways, falling within the scope of the invention as claimed.

What we claim is:

1. In combination with a substantially cylindrical honing spindle longitudinally splined and provided in said spline with a honing member adjustably projecting radially therefrom, a longitudinally slotted sleeve telescopically engaging said spindle and providing a work engaging surface opposed to said honing member, said slot in said sleeve being aligned with said spline whereby said honing member also projects through said slot, and disconnectible interengaging locking means respectively carried by said spindle and sleeve to prevent appreciable relative movement therebetween in a longitudinal direction.

2. In combination with a substantially cylindrical honing spindle having a longitudinally extending spline and provided in said spline with a honing member adjustably projecting radially therefrom, a longitudinally slotted sleeve telescopically engaging said spindle and providing a work engaging surface opposed to said honing member, said slot in said sleeve being aligned with said spline whereby said honing member also projects through said slot, and disconnectible locking means for said spindle and sleeve comprising an interengaging projection and recess provided one on the spindle and the other on the sleeve to prevent appreciable relative movement between said spindle and sleeve in a longitudinal direction, relative rotatable movement therebetween being prevented by said honing member when projecting radially from said spline and into said slot.

3. In combination with a substantially cylindrical honing spindle having a longitudinally extending spline and provided in said spline with a honing member adjustably projecting radially therefrom, a longitudinally slotted sleeve telescopically engaging said spindle and providing a work engaging surface opposed to said honing member, said slot in said sleeve being aligned with said spline whereby said honing member also projects through said slot, and disconnectible locking means for said spindle and sleeve comprising a projection on said sleeve adapted to be disposed in a recess provided in said spindle to prevent appreciable relative movement between said spindle and sleeve in a longitudinal direction, relative rotatable movement therebetween being prevented by said honing member when projecting radially from said spline and slot.

4. In combination with a substantially cylindrical honing spindle having a longitudinally extending spline and provided in said spline with a honing member adjustably projecting radially therefrom, a longitudinally slotted sleeve telescopically engaging said spindle and providing a work engaging surface opposed to said honing member, said slot in said sleeve being aligned with said spline whereby said honing member also projects through said slot, and disconnectible locking means for said spindle and sleeve comprising a projection on said sleeve adapted to be disposed in a recess provided in said spindle and communicating with said spline, said locking means preventing appreciable relative movement between said spindle and sleeve in a longitudinal direction and relative rotatable movement therebetween being prevented by said honing member when projecting radially from said spline and slot.

5. A substantially cylindrical honing spindle having a longitudinally extending spline and also having a transverse slot in one wall of said spline, and a honing member in said spline and adapted

to be adjustably projected radially therefrom, said honing member having a pin projecting from one side and disposed in said slot to prevent relative longitudinal movement between said spindle and honing member, in combination with a longitudinally slotted sleeve telescopically engaging said spindle and providing a work engaging surface opposed to said honing member, said slot in said sleeve being aligned with said spline whereby said honing member also projects through said slot, and disconnectible locking means for said spindle and sleeve comprising a projection on said sleeve extending inward and adapted to be disposed in said slot in the spindle to prevent appreciable relative movement between said spindle and sleeve in a longitudinal direction, relative rotatable movement therebetween being prevented by said honing member when projecting radially from said spline and slot.

6. A substantially cylindrical honing spindle longitudinally splined and also having a transverse slot in one wall of said spline, and a honing member in said spline and adapted to be adjustably projected radially therefrom, said honing member having a pin projecting laterally from one side and disposed in said slot to prevent relative longitudinal movement between said spindle and honing member, in combination with a longitudinally slotted sleeve telescopically engaging said spindle and providing a work engaging surface opposed to said honing member, said slot in said sleeve being aligned with said spline whereby said honing member also projects through said slot, and means disconnectibly locking said spindle and sleeve and comprising a pin projecting inward from said sleeve and adapted to be disposed in said slot in the spindle to prevent appreciable relative movement between said spindle and sleeve in a longitudinal direction, relative rotatable movement therebetween being prevented by said honing member when projecting radially from said spline and slot.

7. A substantially cylindrical honing spindle longitudinally splined and also having a transverse slot in one wall of said spline, and a honing member in said spline and adapted to be adjustably projected radially therefrom, said honing member having a pin projecting laterally from one side and disposed in said slot to prevent relative longitudinal movement between said spindle and honing member, in combination with a longitudinally slotted sleeve telescopically engaging said spindle and providing a work engaging surface opposed to said honing member, said slot in said sleeve being aligned with said spline whereby said honing member also projects through said

slot, and means disconnectibly locking said spindle and sleeve and comprising an inturned ear projecting from said sleeve and into said slot in said spindle to prevent appreciable relative movement between said spindle and sleeve in a longitudinal direction, relative rotatable movement therebetween being prevented by said honing member when projecting radially from said spline and slot.

10 8. A substantially cylindrical honing spindle longitudinally splined and also having a transverse slot in one wall of said spline and a recess extending transversely of the spline and inward from the outer surface of the spindle, and a honing member in said spline and adapted to be adjustably projected radially therefrom, said honing member having a pin projecting laterally from one side and disposed in said slot to prevent relative longitudinal movement between said spindle and honing member, in combination with a longitudinally slotted sleeve telescopically engaging said spindle and providing a work engaging surface opposed to said honing member, said slot in said sleeve being aligned with said spline whereby said honing member also projects through said slot, and means disconnectibly locking said spindle and sleeve and comprising a projection on said sleeve adjacent the slot therein and extending into said recess in said spindle to prevent appreciable relative movement between said spindle and sleeve in a longitudinal direction, relative rotatable movement therebetween being prevented by said honing member when projecting radially from said spline and slot.
